UNITED STATES PATENT OFFICE.

EMILE DURAND, OF SALEM, MASSACHUSETTS.

TRACK FOR MOTOR-BOATS.

1,079,901.

Specification of Letters Patent. Patented Nov. 25, 1913.

Application filed April 5, 1913. Serial No. 759,223.

To all whom it may concern:

Be it known that I, EMILE DURAND, a subject of the King of Great Britain, and a resident of Salem, in the county of Essex 5 and State of Massachusetts, have invented certain new and useful Improvements in Tracks for Motor-Boats, of which the following is a specification.

This invention relates to tracks for motor 10 boats adapted to connect two separated ponds or other water surfaces, whereby, without stopping, said motor boat may be run onto said track and with its propeller engaging projecting members thereon be moved over 15 said track from one water surface to another.

The invention consists in two parallel rails having their ends flaring from each other and submerged below the surface of 20 a water area such as a pond, river, or lake, said rails having interposed between them a plurality of projecting members, preferably revoluble, which are adapted to be engaged by the propeller of a motor boat to effect a 25 movement of said boat along the rails of said track.

The invention further consists in certain 30 novel features of construction and arrangement of parts which will be fully understood by reference to the description of the drawings and to the claims hereinafter given.

Of the drawings: Figure 1 represents a longitudinal section of a track embodying the features of the present invention, and 35 showing in section thereon a motor boat adapted to be moved over said track. Fig. 2 represents a plan of said track. Fig. 3 represents a transverse section of said track, showing a front view of a motor boat there- 40 on, and Figs. 4 and 5 represent two forms of revoluble projections with which the propeller of a motor boat is adapted to engage to impart movement to the boat along the track.

45 Similar characters designate like parts throughout the several figures of the drawings.

In the drawings, 10—10 represent two side members or rails having V-shaped de- 50 pressions or grooves 11 therein. These rails are connected by means of sleepers or other cross members 12, and superimposed upon said sleepers 12, and midway between said rails 10 is the member 13 having secured 55 thereto the upwardly projecting studs 14, each of which is surrounded by a cylindrical

member 15, said cylindrical member being prevented from becoming displaced by means of the pins 16 extending through the stud 14. The cylindrical member 15 may be 60 provided if desired with peripheral flanges 17, as indicated in Fig. 5 of the drawings, to reduce the friction when in contact with a movable member.

The rails 10 are adapted to be laid on any 65 surface or ground between two ponds or other water surfaces, and their ends are bent downwardly into these ponds as indicated in Fig. 1 and submerged therein. The ends 18 of the rails where submerged in the 70 water flare away from each other as indicated in Fig. 2 of the drawings. The inner wall of the flaring ends of the rails are cut away, as indicated at 19 in Fig. 2 of the drawings.

The object of the device is to provide a 75 means whereby a peculiar-shaped motor boat 20, such as that disclosed in Letters Patent No. 1,051,833, issued to me on January 28, 1913, may be driven without stopping from one water surface over the tracks laid on land into another pond or water area, the revoluble propeller 21 thereon engaging with the projecting members 14 or 15 to impart movement to said motor boat 80 over said rails 10. This motor boat is provided with keels 22 which run in the bottom of the V-shaped grooves 11 of the rails 10, thereby reducing the friction on the keel as they move along the rail. It is 85 obvious that these keels may be provided if desired with revoluble members to run in the grooves 11, but as this forms no part of the present invention, it is not disclosed in the drawings.

In the operation of the device the motor boat 20 may be driven over the surface of a pond and when it is desired to leave the pond and operate upon an adjacent water surface separated from said pond, the operator directs the motor boat toward the track or runway, and as the boat enters between the flaring ends 18 the revoluble propeller 21 will engage with the projections 15 and as the propeller continues to rotate, the 105 boat will be driven along the rails 10 until it enters the other pond or water area.

The device is intended primarily for amusement parks, but is adapted to be operated in a theater to produce novel stage 110 effects.

It is believed that the operation and many

advantages of this invention will be fully apparent from the foregoing description.

Having thus described my invention, I claim:

- 5 1. In a device of the class described, the combination of a pair of rails; and a plurality of upwardly extending revoluble cylindrical members interposed between said rails and adapted to be engaged by the revoluble propeller of a boat to impart movement to said boat along said rails.
- 10 2. In a device of the class described, the combination of a pair of rails; and a plurality of upwardly extending revoluble cylindrical members having peripheral flanges thereon and interposed between said rails and adapted to be engaged by the revoluble propeller of a boat to impart movement to said boat along said rails.
- 15 3. In a device of the class described, the combination of a pair of rails having V-shaped grooves; and a plurality of upwardly extending cylindrical members interposed between said rails and adapted to

be engaged by the revoluble propeller of a 25 boat to impart movement to said boat along said rails.

4. In a device of the class described, the combination of a pair of parallel rails the ends of which are submerged in water and 30 flare from each other; and means interposed between said rails adapted to be engaged by the revoluble propeller of a boat to impart movement to said boat along said rails.

5. In a device of the class described, the 35 combination of a pair of parallel rails the ends of which are submerged in water and flare from each other; and revoluble means interposed between said rails adapted to be engaged by the revoluble propeller of a 40 boat to impart movement to said boat along said rails.

Signed by me at 4 Post Office Sq., Boston, Mass., this 1st day of April, 1913.

EMILE DURAND.
